UNITED STATES PATENT OFFICE

JOHN S. LAPP, OF LE ROY, NEW YORK, ASSIGNOR TO LAPP INSULATOR COMPANY, INC., A CORPORATION OF NEW YORK

270° CLAMP

Application filed May 23, 1930. Serial No. 455,002.

This invention relates to a clamp which is adapted to clamp a tension member thereto and at the same time turn it through an angle of about 270°.

5 The clamp of the present invention overcomes the disadvantages of prior clamps by providing a strong unitary clamp adapted to be secured to a suitable support or insulator at one end and to clamp the tension member thereto at the other end, at the same time, turning the tension member through an angle of about 270° in its passage through the clamp.

In the accompanying drawing:—

15 Figure 1 is an edge view of a clamp embodying the present invention.

Fig. 2 is a plan view of the same; and

Fig. 3 is a perspective view showing the clamp in use.

20 As will be seen from the drawing, the clamp consists of a unitary member which may be a suitable forging having a substantially circular body portion 10 which may be said to represent a partial turn of a helix, 25 but it will be clear that the ends of the body portion are superimposed and at an angle of about 270° to each other, although it is within the scope of the present invention to vary this angle so that it is greater than 270°. 30 and may approach a complete circle of 360° or it may even be in some cases less than 270°.

Assuming that the clamp body is about 270°, it will be noted that a cable or tension-member receiving groove or channel 11 passes around the outside of the body which is cut out centrally as at 12 forming, roughly speaking, an annulus and projecting from the inner surface of the annulus into the central 40 cut-away portion and in the same plane with the side walls of the groove is the projection 13, the purpose of which will be explained hereinafter.

Extending substantially tangentially from 45 one end of the body portion is an extension 14 which is bifurcated at its extreme end to provide the arms 15 with the apertures 16 passing therethrough and, as shown in Fig. 3, this bifurcated end is adapted to receive 50 the apertured ear of a suitable supporting

means, a pin passing through the whole to secure the clamp in position. The other end of the clamp body also has a substantially tangential extension 17 which is provided with apertured ears 18 and a central 55 strengthening rib 19. A U-bolt 20 having threaded ends is adapted to be passed through the apertured ears of extension 17, nuts 21 being threaded on said bolt ends, thereby clamping the cable or tension member 22 firmly in place, see Fig. 3.

For the purpose of lightening the clamp, the material in the bifurcated, tangential extension 14 may be somewhat cut away as at 23, but not to such an extent as to impair the 65 strength thereof. The groove formed around the body of the clamp and across the face of the extension 17 may vary either in width or in depth or in both, if so desired.

In use, as is clearly shown in Fig. 3, the 70 tension member is threaded around the groove of the body portion emerging at about 270° to its original line of direction, and in order to secure the tension member to the clamp at the desired tautness a block and 75 tackle (not shown) is connected temporarily to the body of the clamp by passing the hook of the block and tackle through the central opening of the clamp, the projection 13 acting to prevent slipping of the hook, so that 80 the tension member may be applied to the clamp and fastened by means of the U-bolt construction to give a predetermined tension on the span of wire as otherwise it would be practically impossible to handle the tension 85 member manually so as to secure the desired degree of tautness in the span. When the tension member is so secured the block and tackle may be removed.

Various modifications, additions, or omissions may be made in the clamp disclosed which is intended to be illustrative more than 90 limitative.

What I claim as new and desire to secure 95 by Letters Patent is:

1. A clamp consisting of a substantially circular body portion having an exterior groove with offset ends for the reception of a tension member, a bifurcated tangential extension at one end adapted to be secured to a 100

suitable support and a tangential extension at the other end having associated means to secure said tension member thereto, the body portion aforesaid being centrally cut out, and 5 a projection extending from the body portion inwardly into said cut out.

2. A clamp having a substantially 270° exteriorly grooved body portion, a tangential extension at one end to secure said clamp to 10 an insulator support or the like, an apertured tangential extension at the other end, a clamping element cooperating with said apertures to secure said tension member to 15 said extension, and an inwardly extending projection on said body portion.

3. A clamp comprising a substantially annular body, having a substantially annular cable receiving groove formed in the outer peripheral face thereof, and an inwardly 20 projecting lug formed on the inner peripheral face thereof, an extension extending substantially tangentially of said body and having a cable receiving groove formed therein and forming a continuation of the groove of 25 said body, and a second extension extending substantially tangentially with relation to said body and at an angle to said first mentioned extension, integrally formed with said body and adapted to be secured to a support.

30 4. A clamp comprising a substantially annular body, having a substantially annular cable receiving groove formed in the outer peripheral face thereof, and an inwardly projecting lug formed on the inner peripheral 35 face thereof, an extension extending substantially tangentially to said body and having a cable receiving groove formed therein constituting a continuation of the groove of 40 said body, means associated with said extension for securing a cable in place in said groove, and a second integrally formed extension extending substantially tangentially with relation to said body and at an angle to 45 said first mentioned extension, and adapted to be secured to a support.

5. A clamp adapted to turn a cable through an angle of about 270° and to hold said cable in such position comprising a peripherally 50 grooved body member so constructed and arranged as to effect the same, said body member having a unitary extension directly connected to a suitable support and lying substantially in the plane of said body member, a second extension on said body member at 55 the exit end of said groove which is widened and provided with lateral apertured ears between which said groove continues, the entering end of said groove being coterminous with the body member, and means cooperating 60 with said exit end for anchoring said cable in position.

6. A clamp adapted to turn a cable through an angle of about 270° and to hold said cable in such position, comprising a peripherally 65 grooved annular body member so constructed

and arranged as to effect the same, said body member having a unitary extension directly connected to a suitable support and lying substantially in the plane of the body member, the entering end of the groove being coterminous with said body member, a tangential extension at the exit end of the groove in said body member, said latter extension having a groove as a continuation of the groove in said body member, a pair of lateral apertured ears at the end of said latter extension and a longitudinally extending rib on the underside of said last extension.

7. A clamp adapted to turn a cable through an angle of about 270° and to hold said cable in such position, comprising a peripherally grooved annular body member so constructed and arranged as to effect the same, said body member having a unitary extension directly connected to a suitable support and lying substantially in the plane of the body member, the entering end of the groove being coterminous with said body member, a tangential extension at the exit end of the groove in said body member, said latter extension having a groove as a continuation of the groove in said body member, a pair of lateral apertured ears at the end of said latter extension and a longitudinally extending rib on the underside of said last extension, said rib rising from a minimum height forwardly and rearwardly of said lateral ears to a maximum height at a point in lateral alignment with said ears but underlying the groove at that point.

8. A clamp adapted to turn a cable through an angle of about 270° and to hold said cable in such position, comprising a peripherally grooved annular body member so constructed and arranged as to effect the same, said body member having a unitary extension directly connected to a suitable support and lying substantially in the plane of the body member, the entering end of the groove being coterminous with said body member, a tangential extension at the exit end of the groove in said body member, said latter extension having a groove as a continuation of the groove in said body member, a pair of lateral apertured ears at the end of said latter extension, and a longitudinally extending rib on the underside of said last extension, said rib rising from a minimum height forwardly and rearwardly of said lateral ears to a maximum height at a point in lateral alignment with said ears but underlying the groove at that point, the walls forming the groove in said last extension being cut away at said ears.

9. A clamp adapted to turn a cable through an angle of about 270° and to hold said cable in such position, comprising a peripherally grooved annular body member so constructed and arranged as to effect the same, said body member having a unitary extension directly connected to a suitable support and lying

- substantially in the plane of the body member, the entering end of the groove being co-terminous with said body member, a tangential extension at the exit end of the groove
5 in said body member, said latter extension having a groove as a continuation of the groove in said body member, a pair of lateral apertured ears at the ends of said latter extension and a longitudinally extending rib
10 on the underside of said last extension, and a U-bolt adapted to have its threaded legs pass through the ears aforesaid and its connecting portion across the groove opposite the rib.
15 In testimony whereof, I have hereunto subscribed my name, May 16, 1930.
